US00D642262S

(12) **United States Design Patent**
Wagner

(10) **Patent No.:** **US D642,262 S**
(45) **Date of Patent:** **** Jul. 26, 2011**

(54) **INSTRUMENT FOR LAPAROSCOPIC
PROCEDURE**

(75) Inventor: **Sebastian Wagner**, Bretten (DE)

(73) Assignee: **Karl Storz GmbH & Co. KG**,
Tuttlingen (DE)

(**) Term: **14 Years**

(21) Appl. No.: **29/379,036**

(22) Filed: **Nov. 12, 2010**

(57) **CLAIM**

The ornamental design for an instrument for laparoscopic procedure, as shown and described.

DESCRIPTION

FIG. 1 is a left side perspective view of an instrument for laparoscopic procedure according to the present invention.

FIG. 2 is a right side perspective view of the instrument for laparoscopic procedure of FIG. 1.

FIG. 3 is a top perspective view of the instrument for laparoscopic procedure of FIG. 1.

FIG. 4 is a bottom perspective view of the instrument for laparoscopic procedure of FIG. 1.

FIG. 5 is a front perspective view of the instrument for laparoscopic procedure of FIG. 1.

FIG. 6 is a rear perspective view of the instrument for laparoscopic procedure of FIG. 1; and,

FIG. 7 is a three quarter perspective view of the instrument for laparoscopic procedure of FIG. 1.
